UNITED STATES PATENT OFFICE.

JOHN W. PAGE, OF QUITMAN, ARKANSAS.

RAILWAY SIGNALING DEVICE.

1,042,028.

Specification of Letters Patent.

Patented Oct. 22, 1912.

Application filed April 1, 1912. Serial No. 687,731.

To all whom it may concern:

Be it known that I, JOHN W. PAGE, a citizen of the United States, residing at Quitman, in the county of Cleburne and State of Arkansas, have invented certain new and useful Improvements in Railway Signaling Devices, of which the following is a specification, reference being had to the accompanying drawings.

10 This invention comprehends certain new and useful improvements in railway signaling devices, and the invention has for its primary object a simple and efficient construction of mechanism of this character, whereby the engineer of a train may at all times keep the road clear ahead of him and apprise others in advance by displaying danger signals that his train is approaching a certain station or block.

15 The invention also has for its object a simple and efficient construction of mechanism of this character which will be practically automatic in all of its workings, which will be easy to maintain and not liable to get out of order, and which will include trip levers arranged at predetermined intervals along the track, whereby when a train approaches a certain point, say one station on the road, a device carried by the

20 engine will engage one of said trip levers and immediately a danger signal at the next station will be brought into view, while subsequently, after the train has reached such signal, the trip lever at the signal station will be also engaged by the device carried by the locomotive and the signal automatically returned to its "clear track" position. And the invention also aims to generally improve this class of devices and to render them

25 more useful and commercially desirable.

With these and other objects in view, as will more fully appear as the description proceeds, the invention consists in certain constructions, arrangements and combinations of the parts that I shall hereinafter fully describe and claim.

For a full understanding of the invention, reference is to be had to the following description and accompanying drawings in

50 which.

Figure 1 is a perspective view of one part of my improved railway signaling mechanism; Fig. 2 is a vertical transverse sectional view of another part of the apparatus; Fig. 3 is a sectional view of the part illustrated in Fig. 1; Fig. 4 is a perspective

view in the nature of a diagram; and Fig. 5 is a horizontal section of the device illustrated in Figs. 1 and 3.

Each of my improved signaling devices 60 for railway work, includes a battery box 1 intended to be located alongside of the track at a station or other predetermined point, said box, in the present embodiment of the invention, being provided on its interior 65 with a ledge or platform 2, upon which a relatively stationary contact plate 3 is mounted. A contact key 4 is held by a supporting arm 5 in juxtaposition to and normally slightly spaced from the contact plate 70 3, said supporting arm 5 being secured at one end to one wall of the box 1 and being held in its normal elevated and inoperative position by a spring 6. An actuating rod 7 is secured at its lower end to the supporting 75 arm 5 and extends upwardly through an opening 8 formed in the top of the box, the upper end of the rod 7 protruding, as clearly illustrated in the drawings, and being designed for engagement by a cam 9 formed 80 on a trip lever 10 which is fulcrumed in between standards 11 supported on the top of the box and which is held normally in an upright position by means of a spring 12.

My invention also includes a motor box 13 85 which is also disposed along the track and located at any predetermined point, say at the next station from the station or point where the battery box 1 is located. An electric motor 14 is supported within the box 90 13 with its shaft 15 disposed vertically, said shaft being secured at one end to a vertically disposed staff 16 which projects up through an opening 17 formed in the top of the box 13. A transversely disposed and vertically projecting stand 18 is mounted on the top of the box 13, said stand being formed with openings 19 and 20 on opposite sides of the staff 16, through which white and red lights are designed to show, the suitable lanterns 10 for this purpose being mounted on the box behind the stand. The stand is also formed in one face with a cavity or recess 21 designed to partially or entirely house the staff. A flag 22 which is painted red on one side and white on the other and which may be in the form of a sheet metal plate or the like, is secured to the staff 16 in perpendicular relation thereto and is designed to be swung over from one side of the stand to the 110 other as the staff 16 is rotated in one direction or the reverse. A cable 23 is secured to

the staff 16, said cable extending through an opening 24 formed in the wall of the cavity 21 and being secured at its other end to a spring 25 which is connected to a trip lever 26 normally held in a vertical position by a spring 27. By means of the spring 25 that is secured to the cable, the connection between the trip lever 26 and staff 16 will be permitted to yield so as to avoid strain upon the parts in the operation of the device.

In carrying out my invention, one lead 28 of the motor 14 is connected to one terminal 29 of the battery 30 in the box 1. The other lead 31 of said motor is connected to the key 4 and the other terminal 32 of the battery 30 is connected by a rod 33 with the relatively stationary contact plate 3.

From the foregoing description in connection with the accompanying drawings, the operation of my improved railway signal will be apparent.

In the practical use of the device, when a train approaches the point where the battery box 1 is located, the engineer will move into operative position some device on the locomotive, whereby such device will move in a path where it will strike the trip lever 10. This device which is carried by the locomotive is not shown, nor is it specifically described, as it may be of any desired form or construction, and is of itself no part of the present invention. As the lever 10 is tripped, it is obvious that its cam 9 will press downwardly upon the actuating rod 7 and consequently, the circuit will be closed by the engagement of the key 4 with the relatively stationary contact plate 3. Thus, the motor 14 will operate to turn the staff 16 in a direction to swing the flag 22 around so that its red side will show by day and the red light will be exposed to view by night. Thus, the engineer of the train may keep his track clear ahead of him, and as the locomotive reaches the trip lever 26, it will operate the latter and such lever will be moved in a direction to pull upon the cable 23 so as to return the staff 16 to its initial position with the white side of the flag 22 showing by day and the white light by night, indicating that the road is clear. Preferably, the motor box 13 is provided on its top with a spring catch 34 designed to engage the flag 22 when it is swung over by the operation of the motor 14, it being, of course, understood that this catch will readily yield so as to release the flag when the same is returned to its initial or "clear track" position by the actuation of the trip lever 26. Although the engagement of the device carried by the locomotive or car with the lever 10 does not continue for any great length of time, yet it rides over and upon said lever and engages it long enough for the motor 14 to act in the desired way, for it will be understood that such motor is of relatively

light voltage and sensitive to relatively light currents, as it is only required to swing the flag 22 through a short arc, and hence, is not required to run a long time. It is manifest that the motor is a light one, owing to the fact that otherwise should the current remain closed after the flag 22 has been swung around as far as possible, there would be a tendency to injure the parts.

While the accompanying drawings illustrate what I believe to be the preferred embodiment of my invention, it is to be understood that the invention is not limited thereto, but that various changes may be made in the construction, arrangement and proportions of the parts without departing from the scope of the invention, as defined in the appended claims. It is also to be understood that there is a signal and a battery box with its correlated devices at each point or station along the road.

What I claim is:

1. In a railway signal of the character described, an electric motor, a circuit therefore, arranged to be closed at a remote point, a box in which said motor is mounted with its shaft disposed in a vertical position, the box being formed in its top with an opening, a vertically disposed staff mounted in said opening and connected at its lower end to the shaft of the motor, a stand mounted on the top of the box and formed with openings for light to shine therethrough on opposite sides of said staff, a signal flag projecting horizontally from and secured to said staff and designed to be swung over the close one of said openings upon the actuation of the motor, and a trip lever operatively connected to said staff and designed to move the same in a direction to swing the flag over the other opening.

2. In a railway signal of the character described, an electric motor, a circuit therefore, arranged to be closed at a remote point, a box in which said motor is mounted with its shaft disposed in a vertical position, the box being formed in its top with an opening, a vertically disposed staff mounted in said opening and connected at its lower end to the shaft of the motor, a stand mounted on the top of the box and formed with openings for light to shine therethrough on opposite sides of said staff, a signal flag projecting horizontally from and secured to said staff and designed to be swung over to close one of said openings upon the actuation of the motor, a cable secured at one end to the staff, and a trip lever connected to the other end of said cable, for the purpose specified.

3. In a railway signal of the character described, an electric motor, a circuit therefore arranged to be closed at a remote point, a box in which said motor is mounted with its shaft disposed in a vertical position, the box being formed in its top with an opening,

vertically disposed staff mounted in said opening and connected at its lower end to the shaft of the motor, a stand mounted on the top of the box and formed with openings 5 for light to shine therethrough on opposite sides of said staff, a signal flag projecting horizontally from and secured to said staff and designed to be swung over to close one of said openings upon the actuation of the 10 motor, a cable connected at one end to said

staff, a trip lever, and a spring connecting the other end of said cable to the trip lever, for the purpose specified.

In testimony whereof I hereunto affix my signature in the presence of two witnesses. 15

JOHN W. PAGE.
